PLUNGER-TYPE FOUNTAIN PEN

Lawrence E. Harbison, Berkeley, Calif.

Application May 6, 1947, Serial No. 746,373

2 Claims. (Cl. 120—47)

1

This invention relates to fountain pens, and more particularly to an improved construction of sacless or plunger type fountain pens.

One of the primary objects of this invention is to provide a plunger-type pen, wherein the operating means for the piston or plunger comprises a plurality of telescoping parts which in the retracted position of the piston will occupy a minimum of space.

Another object of this invention is to provide a plunger-type fountain pen wherein slight motion of the push-button will be multiplied in moving the filling plunger.

Other objects will appear to those skilled in the art from a reading of the following specification.

The accompanying drawings illustrate a preferred embodiment of the invention, but it is understood that modifications may be made therein without departing from the spirit of the invention as hereinafter claimed.

Figure 1 represents an elevation of the filling mechanism as applied to the barrel of a fountain pen, the mechanism being shown in retracted or inoperative position.

Figure 2 shows the same mechanism in extended position, with the push-button pushed in to empty the pen.

Figure 3 is a horizontal section taken on the line 3—3 of Figure 2.

Figure 4 is a horizontal section taken on the line 4—4 of Figure 2.

Figure 5 is a horizontal section taken on the line 5—5 of Figure 2.

Figures 6, 7, and 8 are detailed elevations of portions of the filling mechanism.

The filling mechanism forming the subject matter of this invention is adapted to be inserted within the barrel of a fountain pen.

The filling mechanism comprises a push-button 6 that is accessible from the end of the pen and that is operable to empty and fill the pen. Fixed to the underside of the push-button 6 is a push-rod 10, and fixed to the bottom of the push-rod 10 is a hollow sleeve 11. Telescopically positioned within the hollow sleeve 11 is another sleeve 12, and within the hollow sleeve 12 is still another hollow sleeve 13.

Surrounding the push-rod 10 and secured against longitudinal movement is a hollow sleeve 14, of a larger diameter than the sleeve 11. Outside the hollow sleeve 11 is another sleeve 15, and outside the sleeve 15 is still another hollow sleeve 16.

A piston rod 20 is adapted to slide within the

innermost sleeve 13. A piston 21 is attached to the bottom of the piston rod 20, and is operable to empty and fill the pen.

The motion of the push-rod 10 is communicated to the piston rod 20 in such a way that a very slight movement of the push-rod 10 will be magnified in the movement of the piston rod 20.

A collar 31, attachable to or forming part of 10 the fountain pen at the top thereof, provides a guideway and a stop for the push-button 6 and the push-rod 10. The push-rod 10, illustrated as being hexagonal in cross section, is adapted to slide axially of the pen, but not to rotate. 15 Of course, the sleeve 11, which is attached to the push-rod 10, will also slide. The sleeve 11 is provided with a series of helical slots 41, which are twisted at least fifty degrees with respect to the horizontal. 20 The upper end of the sleeve 14 is supported by a horizontal flange 44 fixed to the collar 31, so that the sleeve 14 may rotate, but not move longitudinally. The lower end of the sleeve 14 is provided with a diametral pin 45, which engages the helical groove 41 in the sleeve 11. It will be obvious, therefore, that as the push-rod 10 is depressed, the sleeve 11 will travel downwardly without rotation, and that the sleeve 14 will rotate without sliding.

25 The sleeves 15 and 16 are slidable with respect to each other and with respect to the sleeve 14. For this purpose, the sleeves 14, 15 and 16 are made hexagonal in shape, as shown most clearly in Figure 4. The sleeves 14, 15 and 16 are adapted to nest within one another, so that all three may rotate together. The push-rod 10 is also hexagonal, and the opening in the collar 31 is shaped in conformity therewith, so that the push-rod 10 is kept from rotation. 30

35 The sleeves 15 and 16 are slidable with respect to each other and with respect to the sleeve 14. For this purpose, the sleeves 14, 15 and 16 are made hexagonal in shape, as shown most clearly in Figure 4. The sleeves 14, 15 and 16 are adapted to nest within one another, so that all three may rotate together. The push-rod 10 is also hexagonal, and the opening in the collar 31 is shaped in conformity therewith, so that the push-rod 10 is kept from rotation.

40 The inner sleeves 11, 12 and 13 are circular, as is also the piston rod 20.

45 As hereinbefore mentioned, the hexagonal sleeve 14 cannot slide, but is permitted to rotate on the flange 44. When the push-rod 10 is depressed, carrying with it the inner circular sleeve 11, the pin 45 on the sleeve 14 rides in the helical grooves 41 of the inner sleeve 11, so that the sleeve 14 is forced to rotate. As a result, the sleeve 15 nested about the sleeve 14 will rotate with it, and the outermost hexagonal sleeve 16 that is nested about the sleeve 15 will also rotate.

50 As the push-rod 10 and its attached sleeve 11 are depressed, the outer sleeves 15 and 16 will also be depressed.

The sleeve 14, of course, will not slide longi-

tudinally. At the same time, all three outer sleeves 14, 15 and 16 are rotating. The outermost sleeve 16 has a lower portion 48 that is secured to the sleeve 12, so that as the sleeve 16 is rotated on the sleeves 14 and 15, it will carry with it in rotation the sleeve 12.

The cylindrical surface of the sleeve 12 is provided with a helical slot or groove 50, the twist of the groove 50 being less than forty degrees. This groove 50 runs in a direction opposite to that of the helical groove 41 in the sleeve 11. The bottom of the sleeve 11 is provided with a radial pin 52 that is adapted to ride in the helical groove 50 of the sleeve 12, so that as the sleeve 12 is rotated by the action of the outermost sleeve 16, the pin 52 on the sleeve 11 rides in the groove 50 of the sleeve 12 to unscrew the latter sleeve 12 from the sleeve 11.

The innermost sleeve 13 is rigidly secured at its top to the top of the sleeve 12, Figure 2. The sleeve 13 is carried bodily by the sleeve 12 and turns and moves axially with the sleeve 12. This sleeve 13 is also provided with a helical slot or groove 55, and the upper portion of piston rod 20 is provided with a radial pin 56 adapted to ride in the groove 55 from within the innermost sleeve 13. The twist of the groove 55 in the innermost sleeve 13 is approximately thirty-five degrees or less.

The elliptical piston 21 prevents the rod 20 from rotating at all times. As the inner sleeve 13 rotates and descends longitudinally with the sleeve 12, the coaction of the pin 56 in the spiral groove 55 will cause the rod 20 and piston 21 to be moved further longitudinally downwardly. The groove 55 in the sleeve 13 is also in the same direction as the groove 41 in the sleeve 11, so that the net result of the extension of the various members will be a travel of the piston rod 20 to a much greater extent than that of the push-rod 10.

A coil spring 60 has one end anchored to the collar 31 by means of a set-screw 61, and the lower end of the spring 60 is secured to the hexagonal sleeve 15 by means of another set-screw 62. Pressure of the push-button 6 will be asserted against the force of the spring 60, and after pressure is released from the push-button 6 the spring 60 will retract all the members to their inoperative positions.

The piston 21 is screw-threaded to the bottom end of the piston rod 20, and comprises two cup leathers 70 and 71, between the two cup leathers 70 and 71 is positioned a thin strong disc 72, preferably of metal. Above the upper cup leather 70 is a rubber washer 73 having an upstanding flange 74. The barrel 5 of the fountain pen is provided with a circular ridge 80 having a downwardly extending flange 81. The ridge 80 is so positioned in the barrel 5 of the fountain pen that in the retracted position of the plunger mechanism the piston 21 will abut the lower surface of the ridge 80 in such a manner that the flange 74 of the rubber washer 73 will mesh with the flange 81 of the ridge 80 to form a tight seal, thereby preventing passage of ink above the ridge 80.

The disc 72 is made elliptical, and the cooperating surface of the barrel 5 is also made elliptical, to prevent rotation of the piston 21 and the piston rod 20 in the barrel 5. If desired, the cup leathers 70 and 71 may also be made elliptical. It will be apparent that portion of the barrel between the ridge 80 and the reservoir of ink below the lowermost position of the piston

21 will have the elliptical shape alluded to, to prevent rotation of the piston 21 and the piston rod 20. That portion of the barrel 5 above the ridge 80 may be made elliptical or circular, but in any event there must be no interference with the rotation of the hexagonal sleeves 14, 15 and 16 in any portion of the barrel.

The cylindrical surface 85 of the collar 31 may be threaded to receive a cap for the purpose of protecting the push-button 6.

In the operation of the device, the push-button 6 is depressed, and the downward motion of the push-rod 10 is communicated to a much greater degree to the piston rod 20, both of the rods moving axially of the barrel 5 of the fountain pen. The cup leathers 70 and 71 will rub against the inside of the barrel 5, and the piston 21 will empty the ink from the pen. If there is no ink left in the pen, the air will be expelled. When pressure on the push-button 6 is released, the spring 60 will promptly retract all the sleeves and move the piston 21 upwardly, creating a suction very rapidly and filling the pen with ink from the reservoir. The upward movement of the piston 21 will be stopped by the circular ridge 80, as the rubber washer 73 will be pressed against the ridge 80 and also against the walls of the barrel 5 to doubly seal the pen against leakage.

30 The angular pitch of the grooves in the sleeves will be one of the factors determining the multiplication of the movement of the piston rod 20 with respect to the push-rod 10.

What is claimed is:

35 1. In a plunger-type fountain pen, an outer barrel constituting an ink reservoir and having a non-circular bore, a non-circular piston mounted within the barrel for reciprocation, a rod secured to the piston and having a radial projection, an innermost sleeve slidably receiving the rod and having a spiral groove to receive the radial projection of the rod, a second sleeve surrounding the innermost sleeve and secured to the innermost sleeve to move axially and to rotate with the innermost sleeve as a unit, the second sleeve having a spiral groove formed therein, an outermost sleeve slidably receiving the second sleeve and having a radial projection engaging within the spiral groove of the second sleeve, the outermost sleeve having a spiral groove formed therein, a first polygonal tube rotatably mounted within said barrel and receiving the outermost sleeve, a radial projection carried by said tube and engaging in the spiral groove of the outermost sleeve, a second polygonal tube surrounding said first tube and all of said sleeves and adapted to turn with said first tube and to move longitudinally thereof, a third polygonal tube surrounding said second tube and arranged adjacent to the innermost and second sleeves and having one end secured to an end of the second sleeve, the third tube being rotatable with the first and second tubes and shiftable longitudinally with respect thereto, a push rod secured to one end of the outermost sleeve and extending through the first tube and beyond one end of the first tube and being longitudinally shiftable and held against rotation, whereby longitudinal movement of the push rod will impart exaggerated longitudinal movement to the piston, and a spring connecting the push rod and barrel and serving to hold the push rod in a retracted position.

75 2. In a plunger-type fountain pen, an outer barrel constituting an ink reservoir and having

a non-circular bore, a non-circular piston mounted within the barrel for reciprocation and held against rotation, a rod secured to the piston and having a radial pin, an innermost sleeve slidably receiving the rod and having a spiral groove to receive the radial pin of the rod, a second sleeve surrounding the innermost sleeve and extending for substantially the entire length of the innermost sleeve and secured thereto to move axially and to rotate with the innermost sleeve as a unit, the second sleeve having a spiral groove formed therein, an outermost sleeve slidably receiving the second sleeve and having a radial pin engaging in the spiral groove of the second sleeve, the outermost sleeve having a spiral groove formed therein, a first polygonal tube rotatably mounted within the barrel and held against longitudinal movement therein, the first polygonal tube receiving therein the outermost sleeve and having a radial pin engaging in the spiral groove of the outermost sleeve, a second polygonal tube surrounding the first polygonal tube and all of said sleeves and adapted to turn with the first polygonal tube and to move longitudinally thereof, a third polygonal tube surrounding the second polygonal tube and arranged adjacent to the innermost and second sleeves and having one end secured to an end of

10 the second sleeve, the third polygonal tube being rotatable with the first and second polygonal tubes and shiftable longitudinally with respect thereto, the polygonal tubes being telescopically nested about all of said sleeves, said sleeves being telescopically arranged, a push rod secured to one end of the outermost sleeve and extending through the first polygonal tube and being longitudinally shiftable therein but held against rotation, and a spring connected with the barrel and with one of said polygonal tubes and serving to bias the tubes, sleeves, piston and push rod in retracted positions.
